BATH AND SHOWER SUPPLY FITTING WITH DEVIATOR SPOUT

Filed May 26, 1945

Fig. 1.

UNITED STATES PATENT OFFICE

2,507,467

BATH AND SHOWER SUPPLY FITTING WITH
DEVIATOR SPOUT

Edward A. Fredrickson, Chicago, and James R. Turek, Berwyn, Ill., assignors to Crane Co., Chicago, Ill., a corporation of Illinois

Application May 26, 1945, Serial No. 596,006

5 Claims. (Cl. 137—69)

1

This invention relates generally to a novel combination bath and shower supply fitting with deviator spout suitable for use with bathtubs and provided with means whereby the water from the spout may be diverted to a shower head.

More particularly this invention relates to a device which constitutes a modification of the type of structure disclosed in U. S. Patent #2,022,875 granted December 3, 1935.

In connection with the installations involving a concealed water supply for bathtub and shower uses, it has long been a problem to provide a fitting combination preferably of a compact one-piece body construction and employing all of the features usually present in the old designs having a multiplicity of parts such as two valves, a supply T, ejector and auxiliary jet fittings and with supply piping therebetween.

Another object is to provide a device of the character hereinafter described eliminating the necessity for employing an auxiliary jet.

A further improved object is to provide a compact structure to replace the previous unit which comprised many parts, the present fitting being capable of having the inlet supply and the various discharge outlets integrally in a single novel casting.

Another object is to provide a combined bath and shower supply fitting in which valve controls for the hot and cold water supplies are housed therein.

A further object is to provide a combined shower supply fitting with a deviator in which the manufacturing cost thereof is reduced to a minimum and in which the simplicity of the device makes the installation of the fitting less expensive to accomplish.

Other objects and advantages will become apparent upon proceeding with specification read in light of the accompanying drawing, in which

Fig. 1 is a vertical longitudinal sectional view of the combination spout and deviator valve adapted for concealed shower connection and taken on the line 1—1 of Fig. 2.

Fig. 2 is a plan view of the device referred to in Fig. 1.

Similar reference characters refer to similar parts throughout the several views.

Referring now to Fig. 1, the spout is formed in the usual manner having a spout 1 with an enlarged body portion 2 having threads 3 for connection with a novel manifold inlet fitting 4 suitably connected as indicated. The portion 2 of the spout is provided with an annular partition 5 extending transversely across the body 55

and having a valve port and seat 6 at approximately its center adapted to be closed by a vertically disposed reciprocably movable diverter valve 7. The latter valve has the stem 8 affixed to a side portion thereof so that upon upward movement of the handle 9, the valve 7 may be moved vertically across the seat 6 to thereby shut off the valve port and seat 6 of the discharge spout 1.

10 As more clearly shown in Fig. 2, the end portions of the fitting 4 are provided with the oppositely disposed side extensions 11 and 12 serving as the inlet supplies for hot water and cold water from the fittings 14 and 15, the latter being connected to a hot water supply pipe 20. A similar pipe (not shown) is connected to the fitting 14 for the cold water supply. As indicated in Fig. 1, the latter portion of the fitting is preferably installed behind a wall line. The fitting 4, in addition to having the inlet passages 16 and 17 leading respectively from the inlet connections 11 and 12, is also provided at its central portion with a mixing chamber 18 from which a jet member 19 leading directly to the diverter valve port 6 and is threadedly connected thereto as at 21. The jet member 19 serves as a means for projecting the mixed inlet stream supply past the seat 6 and thence into the spout 1 when the valve 7 is open as indicated in Fig. 1. It will be noted, as illustrated, that the inner end portion of the jet 19 projects substantially within the diverter valve chamber 22 and preferably extends closely adjacent to the outlet orifice of the seat 6 thereby reducing to a minimum, when the diverter valve is open, the amount of water impingement which might otherwise occur to create objectionable turbulence within the chamber 22. Such condition of turbulence would be objectionable for 20 reasons hereinafter explained in detail. The jet 19 may of course be made integral with the fitting 4, and not necessarily attached as indicated.

Proceeding now with a further description of 45 the structure and which relates more significantly to our novel contribution, the manifold or multiport fitting 4, as shown more clearly in Fig. 1, is provided at its upper portion with an outlet extension 23 which may be threaded as at 24 or otherwise connected to a suitable pipe 10 leading to an overhead shower head (not shown). It will be apparent that so long as the valve 7 is in the open position shown in Fig. 1, the discharging mixed stream will be projected 50 without substantial back pressure past the seat

orifice 6 and therefore no substantial amount of water will accumulate within the valve chamber 22. As a matter of fact, flow under high velocity actually creates a partial vacuum which substantially keeps the chamber free of water accumulation. However, when the handle 9 in actuating the valve member 7 is lifted, the latter member will be slidably moved across the seat 6 and with the water from the supply lines continuing to enter, assuming the valves generally indicated at 26 and 27, respectively, to be open, will allow for the water to strike the surface of the valve 7 opposite the chamber 22 thereby immediately filling the chambers 22 and 25 and causing the water therewithin to be discharged through the outlet 23 and into the vertically extending pipe 10 having connected therewith a shower head (not shown). The arrangement just described permitting the water to move back over the exterior of the jet 19 and outwardly into the superposed outlet 23 is believed to be new in a fixture of this type for concealed installations.

In summary, concealed fittings of this character heretofore have employed an auxiliary jet to control the flow of water through the spout seat after it was discharged from an ejector fitting concealed behind the wall line. The outlet to the shower head was contained in the said ejector fitting. In the instant contribution, one jet member has been eliminated and provision is made for a multi-port fitting which connects directly to the spout, shower outlet, hot and cold water piping. The novel fitting also contains the jet means and the hot and cold water valve trimmings thereby eliminating the numerous joints, which being ordinarily located behind the wall line have been objectionable.

For purpose of finished trim, a plate member 28 may be used having a flange 29 and provided with a threaded set screw 31 which is slipped over the threaded end of the body 2 prior to making the assembly with the fitting 4. Thus it will be apparent that the concealed portions of the assembly behind the wall line will be the supply fittings and the shower discharge pipe. The fitting 4 is sufficiently large with relation to capacity so as to permit the required amount of water to be discharged through the spout 1 and also to the shower pipe 10. The chamber 25 is of substantially annular form and provides for a portion of its extension around the jet 19, as indicated. Of course the annular chamber around the jet 19 may be modified to permit flow of the water over only a portion of the exterior of the jet, as for example, over the top portion only.

As to the valves generally designated 26 and 27, these are of the character shown and described in detail in pending patent application identified as Serial No. 535,728 filed May 15, 1944. They consist primarily of a valve casing 32, having therewithin the reciprocably movable closure member 33, seating at 34, the seat 35 preferably being of a special composition. Within the casing 32 is the apertured sleeve 36 held in position as indicated and at the upper portion thereof the stem 37 is threadedly mounted to provide for the desired opening and closing movements of the valve closure member. The centerpiece 38 is threaded to receive the stem and the operation of the valve is effected by suitable rotation of the handle 41.

Of course the detailed manner in which the fitting 4 is provided with the outlet 23 may vary

quite substantially, for example, it need not necessarily be on the center line of the body 4, as illustrated. Similarly, the outlet need not necessarily be located above the inlet supplies but may be positioned below or at the same level and this is equally true relative to the position of the jet member 19.

It is therefore clear that the precise construction, arrangement and operation of parts, as hereinabove shown and described, is not to be limited to the illustrations shown, but it should be manifest that other operations or modifications in the detailed structure and arrangement than those specifically shown and described may be employed and the device may be adapted for use in various positions and connections without departing from the spirit and scope of our invention. Reservation of the right is therefore made to all such variations and modifications as properly fall within the scope of our improvements and terms of the following claims:

We claim:

1. A combined spout and deviator valve comprising a spout having a chamber, a valve port and seat therein, a valve closure member disposed on the inlet side of the said port movable for closing the said port, actuating means for the said closure member, a body connected to the said spout having at least a pair of integral rearwardly projecting inlet passages, a jet member communicating with said rearwardly projecting inlet passages of the said body and projecting into the spout chamber; the body having at its rearward portion an angularly disposed offset extending outlet passage to a shower supply or the like, said pair of inlet passages being joined by a conduit of substantially U-form, said communication with the said jet member being at the middle of the U-form passage.
2. A combined spout and deviator valve comprising a spout having a chamber, a valve port and seat therein, a valve closure member disposed on the inlet side of the said port movable for closing the said port, actuating means for the said closure member, a body connected to the said spout having at least a pair of integral rearwardly projecting inlet passages, a jet member communicating with said rearwardly projecting inlet passages of the said body, the said jet member being mounted in annular spaced apart relation to the body portion connected to the spout and projecting into the spout chamber, the body having at its rearward portion an angularly disposed offset extending outlet passage to a shower supply or the like, said pair of inlet passages being joined by a conduit of substantially U-form, said communication with the said jet member being at the middle of the U-form passage, a transversely movable cover plate mounted on the said spout, and means for adjustably positioning the said cover plate relative to the said spout.
3. A combined spout and deviator valve comprising a spout having a chamber, a valve port and seat therein, a valve closure member disposed on the inlet side of the said port movable for closing the said port, actuating means for the said closure member, a body having a central hollow portion connected to the said spout and having at least a pair of integral rearwardly projecting inlet passages, a jet member communicating with said rearwardly projecting inlet passages of the said body and projecting from said central portion of the body into the spout chamber, the body having at its rearward portion an angularly disposed offset extending outlet passage to a shower

supply or the like, said pair of inlet passages being joined by a conduit of substantially U-form, said communication with the said jet member being at the middle of the U-form passage, the central portion of the body being spaced from the jet member to provide an annular chamber communicating with the said outlet passage to the shower supply.

4. A combined spout and deviator valve comprising a spout having a chamber, a valve port and seat therein, a valve closure member disposed on the inlet side of the said port movable for closing the said port, actuating means for the said closure member, a body connected to the said spout having at least a pair of integral rearwardly projecting inlet passages, a jet member communicating with said rearwardly projecting inlet passages of the said body and projecting through an annular opening of the body into the spout chamber, the body having at its rearward portion an angularly disposed offset extending outlet passage to a shower supply or the like, the said outlet passage being superposed above a peripheral portion of the jet member and communicating with the annular opening of the body, said pair of inlet passages being joined by a conduit of substantially U-form, said outlet passage being positioned above the said inlet passages.

5. A combined spout and deviator valve comprising a spout having a chamber, a valve port

and seat therein, a valve closure member disposed on the inlet side of the said port movable for closing the said port, actuating means for the said closure member, a body connected to the said spout having at least a pair of integral rearwardly projecting inlet passages, a jet member removably connected with said rearwardly projecting inlet passages of the said body and projecting beyond the said body and in spaced relation thereto within the spout chamber, the said body having at its rearward portion an angularly disposed offset extending outlet passage to a shower supply or the like, said pair of inlet passages being joined by a conduit of substantially U-form, the said outlet passage to the shower supply being positioned between portions of the said U-form conduit.
